UNITED STATES PATENT OFFICE.

SAMUEL JOSEPH LEVI, OF BIRMINGHAM, ENGLAND.

DESIGN FOR A PROTECTOR FOR ARTICLES TO BE WORN ON THE WRIST.

50,558.

Specification for Design.

Patented Apr. 3, 1917.

Application filed November 8, 1916. Serial No. 130,279. Term of patent 7 years.

To all whom it may concern:

Be it known that I, SAMUEL JOSEPH LEVI, a subject of the Kingdom of Great Britain, residing at 32 Regent Place, Birmingham, in the county of Warwick, England, have invented a new, original, and ornamental Design for a Protector for Articles to be Worn on the Wrist, of which the following is a specification, reference being had to the accompanying drawing, forming part thereof.

Figures 1 and 2 are a plan and edge view

respectively of a protector for use with wristlet watches and other similar articles to be worn on the wrist and showing my new design.

I claim:—

The ornamental design for a protector for articles to be worn on the wrist, as shown.

SAMUEL JOSEPH LEVI.
